UNITED STATES PATENT OFFICE.

FRIEDRICH WILHELM BRUSCH AND WALTER FRANZ JOSEF BEYER, OF DORTMUND,
GERMANY, ASSIGNORS TO DEUTSCH-LUXEMBURGISCHE BERGWERKS-UND HÜTTEN-
AKTIENGESELLSCHAFT, OF BOCHUM, GERMANY.

APPARATUS FOR THE AUTOGENOUS WORKING OF METALS UNDER WATER.

1,278,429.

Specification of Letters Patent. Patented Sept. 10, 1918.

Application filed May 22, 1915. Serial No. 29,809.

To all whom it may concern:

Be it known that we, FRIEDRICH WILHELM BRUSCH and WALTER FRANZ JOSEF BEYER, both citizens of the German Empire, residing at Dortmund, in the Kingdom of Prussia, German Empire, have invented new and useful Improvements in Apparatus for the Autogenous Working of Metals Under Water, of which the following is a specification.

Our invention relates to apparatus for the autogenous working of metals under water. When working metals under water by means of autogenous burners means must be provided for protecting the flame of the burner from the water and the like. Heretofore it has been suggested to provide a casing surrounding the flame, placing the same on the metal to be worked, and removing the water therefrom. It has also been suggested to provide means in connection with the burner whereby compressed gas is discharged around the burner so as to provide a layer of gas in the form of a cylinder inclosing the flame. Our invention is based on the discovery that the flame can be brought to action under the water without being thus protected by mechanical means and without providing a cylindrical sheet of a gas. We have found that the flame can be thoroughly protected against the water by means of one, two or more jets of a compressed gas which are discharged at the side of the flame and do not form a closed cylindrical sheet. Thereby the consumption of compressed gas is materially reduced as compared to the old method in which the gas surrounded the flame, and as compared to the mechanical means for protecting the flame; our improved apparatus is more simple in operation, and it enables the operator to have access to the point which is being worked and to apply thereto soldering media and the like.

In order that our invention be more clearly understood, an apparatus suitable for carrying the same into effect has been shown by way of example in the accompanying drawing, in which—

Figure 1, is a side view of the burner, and Fig. 2, is a bottom view showing the discharge end of the burner and the nozzles for discharging the jets of gas.

In the example shown in the drawing

the burner is equipped with two nozzles 55 for discharging compressed gas, which nozzles are so disposed as to discharge the jet of compressed gas substantially in a direction parallel to the flame. But we wish it to be understood, that our invention is not limited to the example shown in the drawing, and that the number of nozzles for discharging jets of compressed gas which shows the best results as to economy and efficiency depends on the conditions of each particular case.

Referring now more particularly to the figures, the burner 1 may be constructed in any known or preferred way. As shown it is connected with supply tubes 2 and 3 for hydrogen and oxygen respectively, as is known in the art. For holding the burner in position for working on the metal, the upper surface of which has been indicated in Fig. 1 by the numeral 4, the burner is equipped with wheels 5 which hold the same at the proper distance from the metal, and it is preferably advanced in the direction of the arrow a. For preventing the water from having access to the flame we provide a nozzle or nozzles 6 and 7 which are connected with a suitable supply tube 8 for supplying a suitable compressed gas such as carbonic acid or the like, and we arrange the said nozzle or nozzles in such a way, that the jet of air or gas is discharged therefrom slightly above the lower face of the burner 1. The nozzle or nozzles 6 and 7 for the compressed gas are mounted in such a way, that the direction of the jet discharged therefrom can be varied within certain limits, according to circumstances.

In respect thereof Fig. 1 shows in full lines nozzles 6 and 7 having their axes parallel to the flame of the burner; however, at 10 joints or articulations of any known or suitable construction are provided which permit angular adjustment of said nozzles 6 and 7 within certain predetermined limits, that is, within a small range, such as is for example shown with dotted lines. But in any case, the function of the jet or jets is to guide and protect the flame. Where a single nozzle 6 or 7 for compressed gas is used we prefer to discharge the jet therefrom as nearly as possible parallel to the flame, while in case of a plurality of nozzles 6 and 7 the jets can be slightly inclined.

toward the flame, so that the axial lines of the jets intersect each other below the core 9 of the flame as indicated by the arrows.

The tubes 2, 3, and 8 of the apparatus are rigidly connected together by means of suitable connections or clamps 11, so as to form one single apparatus which can be easily attended to by the diver.

As is shown in the figures, we prefer to dispose the nozzles 6 and 7 a little above the nozzle of the burner. Thereby the jets of compressed gas are not liable to blow out the flame, which might otherwise be the case. In the preferred form shown in the figures the nozzle or nozzles for the compressed gas are arranged in such a way, that the jets discharged therefrom are projected or directed within a plane through which the burner is moved, and so that a jet is produced in front of the burner moving over the metal. Thereby the preheating of the blank is effected more thoroughly, because the water is removed from the surface to be worked. By discharging the jet of gas in a direction parallel to the flame or substantially so and at low velocity, the flame is not deflected and its hottest zone or core 9 not displaced, which would otherwise be the case, where the jet acts at one side of the flame. In some cases we prefer to provide two nozzles for compressed gas for preventing deflection of the flame.

In the type of torch wherein the flame was enveloped in a protecting mantle of air or gas, as carbonic acid gas, the air or gas consumption was so great that a compressing plant was required to supply the same during sub-aqueous operations, and it has been a difficult problem, occupying engineers for some time, to find some way of dispensing with such cumbersome auxiliary apparatus.

We believe we are the first to dispense with such apparatus, and this is due to our discovery that the flame need not be enveloped in a protecting gaseous mantle, so that one or only a few air or gas jets need be used, preferably so directed that these jets will be parallel to the flame. We are thereby enabled to carry out sub-aqueous operations with the torch extending over a long time, and provide the necessary gas supply, say of carbonic acid from the usual carbonic acid bottles or steel flasks, thus dispensing with all compression.

As already mentioned, the one jet or the several jets of compressed gas act so as to guide or steady the flame. Consequently, said jet or jets must as a rule, alter the flame as little as possible, but before all, it is essential that, as already mentioned, the hottest zone or core of the flame be under no circumstances displaced or deflected, because, according to our trials and experience, in sub-aqueous operations, a very important function of the flame is to effect the preheat-

ing of the blank. Now, this preheating can only be reasonably afforded when the hottest point or zone, *i. e.*, the core of the flame, strikes against the blank. Consequently, this is impossible when said hottest portion 70 or core 9 of the flame is deflected by the jet or jets of compressed gas. As a matter of fact in performing our method, the hottest portion of the flame is generally at a distance of about 5 to 8 mm. from the nozzle 75 of the burner, while the flame taken as a whole, is much longer. Therefore, the jet or jets of compressed gas may eventually deform somewhat the flame proper as long as the hottest portion of the flame, *i. e.*, its 80 core, remains intact. As already pointed out, another advantage of the jet or jets of compressed gas is that the same make the blank water-free in the direction of cutting or welding and, what is more, at the very place 85 in which for a successful operation, the blank is to be preheated during the progress of the work.

We claim:

1. In a subaqueous torch, two nozzles arranged side by side, means for ejecting a flame from one of said nozzles, means for ejecting non-combustible gas from the other nozzle while submerged to prevent water from reaching the flame from that side on 95 which the non-combustible gas ejecting nozzle is arranged, the latter being arranged to project the non-combustible gas onto the blank at a point beside the point acted upon by the flame.

2. In a subaqueous torch, a flame ejecting nozzle, a non-combustible gas nozzle arranged in front of and at the back of the flame ejecting nozzle, and means to eject non-combustible gas from the front and 105 rear nozzles to form a substantially flat sheet of non-combustible gas, whereby two sides of the flame are free.

3. In a subaqueous torch, a flame ejecting nozzle, a non-combustible gas nozzle arranged in front of and at the back of the flame ejecting nozzle, and means to eject non-combustible gas from the front and rear nozzles to form a substantially flat sheet of 110 non-combustible gas, whereby two sides of the flame are free, and means on the torch to direct its movement longitudinally of the sheet of gas.

4. In a subaqueous torch, a flame ejecting nozzle, means to move the latter, an angularly adjustable nozzle in front of and at the back of the flame ejecting nozzle and arranged to direct in the plane of movement of the latter, jets slightly inclined toward said flame, whereby the axial lines of 125 the front and rear nozzles intersect each other below the core of the flame without disturbing the core.

5. In a sub-aqueous torch for cutting and welding metals, means for separately sup- 130

plying the constituents of a completely combustible gas mixture, a burner at which said constituents form a flame, means on the burner to direct its movements over the surface of the blank, and angularly adjustable jet devices in front and at the back of the burner and arranged to direct in the plane of movement of the burner and on a portion of the circumference only of the flame jets 5 slightly inclined toward said flame, so that the axial lines of said jets intersect each other below the core of the flame without disturbing said core.

6. In a sub-aqueous torch for cutting and welding metals, means for separately supplying the constituents of a completely combustible gas mixture, a burner at which said constituents form a flame, means on the

burner to direct its movements over the surface of the blank, and angularly adjustable jet devices terminating slightly above the burner opening in front and at the back of the burner, and arranged to direct in the plane of movement of the burner and on a portion of the circumference only of the flame jets 10 slightly inclined toward said flame, so that the axial lines of said jets intersect each other below the core of the flame without disturbing said core.

In witness whereof we have hereunto set 15 our hands in presence of two witnesses.

FRIEDRICH WILHELM BRUSCH,
WALTER FRANZ JOSEF BEYER.
